ABSTRACT OF THE DISCLOSURE

Process for recovery of primary solvent contained in a raffinate stream produced by a primary extraction process, wherein cooling of the raffinate stream inherently produces a relatively stable mist of free primary solvent phase in the raffinate, and said mist interferes with extraction of primary solvent from the raffinate in a subsequent secondary extraction zone utilizing a secondary solvent. The process comprises mixing and cooling the raffinate stream with a stream of primary solvent in a conditioning zone under conditions sufficient to produce a conditioned raffinate free of primary solvent mist and thereby render the raffinate more readily extractable in the secondary extraction zone. The process has particular application where the primary extraction process is an aromatics extraction process, the raffinate comprises non-aromatic hydrocarbons, the secondary extraction zone is an aqueous extraction zone, and the secondary solvent comprises water. Primary solvents recoverable within the scope of the inventive process include sulfolane-type chemicals, sulfolene chemicals, polyethylene glycols, polypropylene glycols, dimethyl sulfoxide, etc.

BACKGROUND OF THE INVENTION

The present invention relates to the solvent extraction of aromatic hydrocarbons from a hydrocarbon charge stream. More particularly, the present invention relates to the recovery of solvent from the non-aromatic raffinate produced by the solvent extraction of aromatic from a hydrocarbon charge stream. Most specifically, the present invention relates to an improved process for the recovery of solvent from the non-aromatic raffinate by means of a secondary extraction process.

It is well known in the art that the non-aromatic raffinate which leaves the extraction zone of an aromatic hydrocarbon extraction process contains solvent. The solvent which is withdrawn in the raffinate stream must be recovered not only because it may interfere with subsequent raffinate processing or ultimate raffinate use, but primarily because continual loss of solvent in the raffinate stream is a prohibitive economic expense in the aromatic extraction process. The recovery of the solvent from the raffinate stream may be accomplished by distillation, or adsorption, or by a secondary solvent extraction process.

A typical solvent which is utilized in commercial aromatics extraction and which may be recovered in accordance with the practice of this invention is a solvent of the sulfolane type. The solvent possesses a five membered ring containing one atom of sulfur and four atoms of carbon, with two oxygen atoms bonded to the sulfur atom of the ring. Generically, the sulfolane type solvents may be indicated as having the following structural formula:

2

wherein R_1 , R_2 , R_3 , and R_4 are independently selected from the group comprising a hydrogen atom, an alkyl group having from one to ten carbon atoms, an alkoxy radical having from one to eight carbon atoms, and an arylalkyl radical having from one to twelve carbon atoms. Other solvents which may be included within this process are the sulfolenes such as 2-sulfolene or 3-sulfolene which have the following structures:

Other typical solvents which have a high selectivity for separating aromatics from non-aromatic hydrocarbons and which may be processed within the scope of the present invention are 2-methylsulfolane, 2,4-dimethylsulfolane, methyl 2-sulfonyl ether, *n*-aryl-3-sulfonyl amine, 2-sulfonyl acetate, diethylene glycol, various polyethylene glycols, dipropylene glycol, various polypropylene glycols, dimethyl sulfoxide, *N*-methyl pyrrolidone, etc.

One specifically preferred solvent chemical which is processed within the scope of the present invention is sulfolane, having the following structural formula:

Because the typical solvents which are utilized in aromatics extraction are water soluble, it is the practice to extract the solvent from the raffinate stream by contact with an aqueous stream in a subsequent secondary extraction means. The extraction of the primary solvent from the raffinate with water as the secondary solvent may be undertaken in any suitable liquid-liquid contacting means as in a tower containing suitable packing such as Berl Saddles or Raschig Rings, or in a tower containing suitable trays, or in a rotating disc contactor (RDC). The solvent may then be readily recovered from the aqueous solution by distillation.

It has been discovered in various commercial aromatics extraction units utilizing glycol solvents and sulfolane solvents, that the recovery of solvent from the raffinate by extraction with water does not correspond to the recovery which is to be anticipated based upon solubility data, and the assumption of reasonable efficiency of the secondary extractor. For example, the loss of sulfolane in the raffinate product has been found to be from five to fifty times as great as anticipated, and such a loss is greatly above what is economically desirable.

It is obvious in the art to provide additional physical stages in the secondary aqueous extractor in order to achieve the required recovery of the primary solvent contained in the raffinate. Such a solution to the problem of poor extraction efficiency is technically feasible, but it is not a preferred solution since it normally requires that the number of physical stages in the aqueous extractor must be more than double. Not only is this a prohibitively uneconomical expedient, but once a commercial unit has been placed on-stream it is often a physical impossibility to modify the existing water wash facility to provide the required additional contacting stages. The preferred solution to the problem is, therefore, to subject the solvent-rich raffinate stream to conditions which will render the raffinate stream more readily extractable in the existing aqueous extraction means.

3
SUMMARY OF THE INVENTION

It is therefore an object of the present invention to provide an improved process for the recovery of water soluble solvent from a non-aromatic raffinate stream by aqueous extraction.

It is a particular object of the present invention to provide a means for the recovery of water soluble primary solvent from a non-aromatic raffinate stream in an aqueous secondary extraction means containing a minimum number of physical stages.

It is a more specific object of the present invention to minimize the number of physical stages in the aqueous extraction means by first subjecting the solvent-containing raffinate stream to conditions sufficient to render the raffinate stream more readily extractible.

It has been determined that these objectives may be achieved by bringing the raffinate stream from the primary extraction zone into contact with a stream of free primary solvent phase in a conditioning zone of high turbulence and reduced temperature before the solvent-containing raffinate stream is introduced into the secondary extraction zone wherein it is contacted with an aqueous secondary solvent.

Therefore in accordance with the practice of the present invention, one embodiment comprises a process for removal of primary solvent from a raffinate stream containing a first concentration of primary solvent, said raffinate being produced by a primary extraction process, which comprises: (a) mixing and cooling said solvent-containing raffinate stream in a conditioning zone with a first stream of said primary solvent under conditions sufficient to produce a conditioned raffinate containing a second concentration of primary solvent below said first concentration; and, (b) passing the resulting mixture into a separation zone maintained under conditions sufficient to produce a second stream of primary solvent and a stream of said conditioned raffinate.

A further embodiment of this invention may be characterised as an improvement in a process for the recovery of primary solvent from a solvent-containing raffinate stream produced by a primary extraction process, wherein cooling of said raffinate stream inherently produces a mist of free primary solvent phase in said raffinate stream, and said primary solvent is recovered from said raffinate stream by contact with a secondary solvent in a secondary extraction zone, the improvement which comprises: (a) mixing and cooling said solvent-containing raffinate stream in a conditioning zone with a first stream of said primary solvent under conditions sufficient to produce a conditioned raffinate substantially free of primary solvent mist and thereby render said raffinate stream more readily extractible in said secondary extraction zone; (b) passing the resulting mixture into a separation zone maintained under conditions sufficient to produce a second stream of said primary solvent and a stream of said conditioned raffinate; and, (c) passing said stream of conditioned raffinate into said secondary extraction zone wherein dissolved primary solvent is extracted therefrom under conditions sufficient to produce a raffinate stream substantially free of primary solvent.

The process of the present invention is clearly set forth in the accompanying drawing which consists of a simplified schematic flow diagram illustrating one broad embodiment.

While the poor recovery of the primary solvent from the raffinate by aqueous extraction may be the result of any number of influences, it is believed that the primary cause is the presence of an entrained free primary solvent phase within the raffinate stream. For example, where sulfolane is the primary solvent, the non-aromatic raffinate leaves the aromatics extraction zone at an elevated temperature in the range of from 150°-350° F., but normally at about 210° F. when the extraction is conducted for recovery of benzene, toluene, and xylene (BTX ex-

traction). The raffinate stream must therefore be passed through a heat exchanger and cooled before it is passed into the aqueous extractor for the recovery of the sulfolane solvent. In cooling the BTX raffinate from 210° F. to 100° F. or less, the solubility of sulfolane in the raffinate is reduced from the range of 1.5 to 2.0 mole percent to the range of about 0.5 to 0.7 mole percent, the solubility of sulfolane being dependent not only upon the temperature of the raffinate but also upon the mole percent of aromatic hydrocarbon contained therein. At 100° F. a separate phase of sulfolane solvent should therefore appear in the raffinate stream.

Samples of a given commercial BTX raffinate stream taken after cooling and prior to its entry into the aqueous extraction column will frequently indicate that the raffinate is not clear and transparent as anticipated, but rather that it is hazy and translucent or even opaque. (This phenomenon is not only observed in sulfolane systems, but in glycol systems as well.) The haze which is contained in the BTX raffinate is comprised of sulfolane which came out of solution upon cooling and which did not coalesce to form a distant sulfolane phase separate from the raffinate phase. It has been determined in the laboratory that this haze or mist of microdroplets of sulfolane cannot be readily coalesced by merely allowing the sample to stand, and that it cannot be readily coalesced by adding dispersed drops of water to the raffinate or by passing dispersed drops of raffinate up through a water phase.

It is therefore speculated that the relatively poor recovery of sulfolane from the raffinate occurs because the haze in the raffinate does not coalesce in the aqueous extractor. Thus the free sulfolane phase which is readily soluble in water remains dispersed in the raffinate and does not come into contact with the aqueous phase and thereby go into solution. It is believed that as the raffinate passes up through the aqueous extractor as a dispersed hydrocarbon phase, the sulfolane in solution within each drop of hydrocarbon will diffuse to the surface of the drop and be transported across the interface of the hydrocarbon and water thereby passing into the aqueous solution. However, the mist of microdroplets of free sulfolane phase within a given drop of raffinate hydrocarbon cannot so migrate and pass into the aqueous solution. As sulfolane passes out of the hydrocarbon solution and into the aqueous phase, the microdroplets of sulfolane will go into solution in the hydrocarbon drop. The drop of hydrocarbon will thereby remain saturated with sulfolane of solution until all microdroplets of free sulfolane are dissolved. It is only at this point then, that the aqueous extraction can be at all effective in reducing the concentration of sulfolane in the raffinate in accordance with the known equilibrium data.

Thus the raffinate is not readily extractible until it has been freed of the haze of sulfolane microdroplets, and it is only then that the aqueous extractor will function as designed. The aqueous extractor means, having been designed on the basis of the 100° F. sulfolane solubility, cannot function as designed since the presence of the sulfolane phase microdroplets within the raffinate phase effectively results in a higher sulfolane concentration which is equivalent to the original solubility of sulfolane in the BTX raffinate at 210° F. The net result is that the concentration of sulfolane in the raffinate leaving the aqueous extractor will be from five to eight times as great as the design concentration.

This problem of haze or mist in the raffinate is even more greatly pronounced in aromatic extraction processes which are not operating for recovery of BTX, and which therefore operate at temperature levels in excess of 210° F. For example, where the extraction of aromatics is conducted on a kerosine stock for smoke point improvement, the non-aromatic raffinate will leave the primary sulfolane solvent extraction zone at a temperature typically in the range of from 280° F. to 300° F. Additionally since smoke point improvement is the primary objective

rather than maximum aromatics recovery, the resulting kerosine raffinate contains a substantially greater amount of aromatic hydrocarbon than does a BTX raffinate. Both the higher temperature and higher aromatic content of the raffinate, therefore, cause the kerosine raffinate to contain a substantially greater amount of dissolved sulfolane solvent than is contained in a BTX raffinate. Thus the haze or mist content of the kerosine raffinate is greater upon cooling to 100° F., and the problems encountered in adequately extracting the primary sulfolane solvent in the aqueous extraction zone are thus aggravated.

It has now been determined that solvent-rich raffinate may be rendered readily extractable by contacting the hazy raffinate stream with a stream of free primary solvent phase under conditions of high turbulence. It is found in the laboratory that if a test tube of hazy raffinate is violently agitated, the haze or mist does not disappear. The ratio of the hydrocarbon phase to the free solvent phase is so high, the sulfolane haze typically comprising only from 0.8 to 1.5 mole percent, that the mist of micro-droplets of free primary solvent phase cannot coalesce despite the turbulence. If the tube of hazy raffinate is given one or two manual shakes with a large volume of free solvent phase, however, the haze or mist of solvent immediately disappears into the free solvent phase leaving a clear transparent supernatant raffinate phase which only contains dissolved primary solvent. The presence of the free solvent phase in the turbulent zone reduces the ratio of the hydrocarbon phase to non-hydrocarbon phase sufficiently to allow the mist of solvent microdroplets to be coalesced into the free solvent phase. This phenomenon can be observed both in sulfolane solvent systems and in glycol solvent systems.

The equivalent effect is achieved in the inventive process by providing that the cooled non-aromatic raffinate is contacted with a stream of primary solvent phase in a conditioning zone of high turbulence before the solvent-containing raffinate is introduced into the aqueous extraction zone. In the practice of the present invention the solvent-containing raffinate will be rendered most readily extractable when the ratio of hydrocarbon phase to non-hydrocarbon phase in the turbulent conditioning zone is reduced to a level in the range of 5:1-1:1.

The inventive process may be more readily understood and the effectiveness thereof illustrated, by now discussing the drawing in light of a specific example illustrating a typical commercial application wherein a kerosine fraction is solvent extracted for smoke point improvement.

DRAWING AND EXAMPLE

An aromatic solvent extraction unit was designed for removing most of the aromatics out of a kerosine fraction in order to improve the smoke point. The kerosine fraction fed to the extraction unit had a boiling range, characterized by true boiling point cut points, of 347° F. to 450° F. The smoke point of this kerosine fraction was 24 mm., and the aromatic content was 27.2 weight percent. The specification product was a raffinate fraction having a smoke point of 35 mm. The kerosine fraction was solvent extracted with a lean solvent composition comprising chemical sulfolane at a kerosine feed rate of 1500 b.p.s.d. to produce a raffinate product meeting the specification smoke point at a rate of 1010 b.p.s.d.

Referring now to the drawing there is shown the defined kerosine feed entering the process of the present invention via line 1 at a rate of 1500 b.p.s.d. or 105.0 moles per hour. (As used herein, moles refers to pound moles.) This kerosine fraction enters the process of the present invention at a temperature of 220° F., and it is passed into an extractor column 2 via line 1 at a pressure of 50 p.s.i.g. Extractor column 2 is operated under extraction conditions sufficient to remove a substantial portion of the aromatic content from the kerosine feed stock. The bottom of extractor 2 is maintained at a temperature of 280° F. and at a pressure of 50 p.s.i.g. The

top of the extractor is maintained at a temperature of 300° F. and a pressure of 15 p.s.i.g. In order to remove the requisite amount of aromatic hydrocarbon from the kerosine feed, a lean primary solvent stream enters extractor 2 via line 3 at a temperature of 300° F. and at a rate of 645.0 mols./hr. As noted hereinabove, this lean primary solvent comprises chemical sulfolane. A net raffinate fraction leaves the top of extractor 2 via line 4 at a temperature of about 300° F. and a pressure of 15 p.s.i.g. This raffinate fraction will be discussed more fully hereinafter.

A rich primary solvent leaves extractor 2 via line 5 at a rate of 682.5 mols./hr. This rich primary solvent comprises 41.5 mols./hr. of aromatic hydrocarbon and 641.0 mols./hr. of sulfolane solvent. The rich solvent is discharged from the bottom of extractor 2 at a temperature of 280° F. and a pressure of 50 p.s.i.g. The rich primary solvent is subsequently combined in line 5 with an additional solvent stream which enters line 5 via line 13 at a rate of 36.8 mols./hr. and at a temperature of 100° F. from a processing source to be disclosed hereinafter.

The resulting mixture of rich primary solvent passes via line 5 at a total rate of 719.3 mols./hr. The solvent stream comprises 41.5 mols./hr. of an aromatic hydrocarbon fraction and 677.8 mols./hr. of the sulfolane solvent. The mixture of rich primary solvent is heated, by means not shown, to a temperature of 370° F., and upon passing through a control valve in line 5, not shown, is flashed into a fractionation zone 6 at a temperature of 330° F. and a pressure of 50 mm. of mercury absolute.

Fractionation zone 6 may typically comprise any type of a distillation column or a plurality of distillation columns. In the instant example, however, fractionation zone 6 comprises a single fractionating column operated under fractionating conditions sufficient to provide an aromatic extract having substantial freedom from the primary solvent, and a lean solvent fraction having substantial freedom from aromatic hydrocarbons. Among the operating conditions utilized within fractionator 6 are a reboiler temperature of 405° F. and a reboiler pressure of 105 mm. of mercury absolute. This fractionation condition results in an aromatic extract which is withdrawn from fractionator 6 via line 7 at a rate of 41.5 mols./hr. or 490 b.p.s.d. In addition, there is withdrawn from fractionator 6 a lean primary solvent fraction comprising the sulfolane solvent, which is withdrawn at a rate of 677.8 mols./hr. at a temperature of 405° F.

The lean primary solvent passing via line 3 is combined with an additional lean solvent fraction entering line 3 via line 8 at a rate of 1.0 mols./hr. and a temperature of 340° F., said fraction being obtained from a source to be described hereinafter. The resulting mixture of lean primary sulfolane solvent is then passed at a temperature of 405° F. into a heat exchanger or cooler, not shown, wherein the lean solvent mixture is cooled to 300° F. The cooled lean primary solvent thereafter passes via line 3 at a rate of 678.8 mols./hr. and a temperature of 300° F. to the vicinity of the extractor 2. The lean primary solvent is there divided into two portions. The first portion of 645.0 mols./hr. is fed into the extractor 2 via line 3 as the lean primary solvent noted hereinabove.

The second portion of the lean primary solvent comprising chemical sulfolane is withdrawn from line 3 via line 9 at a rate of 33.8 mols./hr. and passed into line 4 wherein it is mixed with the kerosine raffinate being discharged at a rate of 67.5 mols./hr. from extractor 2. The kerosine raffinate comprises 63.5 mols./hr. of hydrocarbons and 4.0 mols./hr. of dissolved and entrained sulfolane solvent. The resulting mixture of raffinate from extractor 2 and solvent from line 9, passes via line 4 at a rate of 101.3 mols./hr. and a temperature of 300° F. into a heat exchanger 10 wherein it is cooled to 100° F. before passing into a separator 12 via line 11.

In cooling the kerosine raffinate phase within heat exchanger 10 from a temperature of 300° F. to a temperature of 100° F., a substantial portion of the dissolved sulfolane passes out of solution from the hydrocarbon phase. However, conditions of turbulence within line 4, heat exchanger 10, and line 11 are such that no haze or mist of free sulfolane solvent is contained within the raffinate phase. The presence of the lean solvent stream passing into line 4 via line 9 is sufficient to coalesce all microspheres of free sulfolane solvent phase out of the raffinate phase, and thereby render the raffinate phase substantially free of any haze or mist. The resulting mixture thus produces a conditioned raffinate having contained therein, only an amount of sulfolane dissolved within the kerosine raffinate under equilibrium solubility conditions. The conditioned raffinate is thereby rendered more readily extractable in subsequent aqueous extraction means to be discussed hereinbelow.

The mixture of conditioned raffinate phase and primary sulfolane solvent phase thus enters separator 12 via line 11. The two phases are separated therein into a lean solvent phase and a clear supernatant raffinate phase. The lean solvent phase is withdrawn from separator 12 via line 13 at a temperature of 100° F. and at a rate of 36.8 mols./hr. The lean primary solvent passes via line 13 into line 5 wherein it is mixed with the rich primary solvent leaving extractor 2 as disclosed hereinabove.

The conditioned raffinate leaves separator 12 via line 14 at a rate of 64.5 mols./hr. The conditioned raffinate comprises 63.5 mols./hr. of mist-free kerosine hydrocarbon and 1.0 mols./hr. of dissolved sulfolane solvent. The conditioned raffinate passes via line 14 into a secondary extraction means 15 comprising a typical water-wash tower. Water-wash tower 15 is maintained at a temperature of 100° F., and at a pressure of 80 p.s.i.g. on the bottom and 50 p.s.i.g. at the top. The conditioned raffinate is contacted therein with a lean aqueous solvent or water stream which enters water-wash tower 15 via line 16 at a rate of 81.0 mols./hr. and at a temperature of 100° F. The conditioned raffinate is contacted under conditions sufficient to extract substantially all of the dissolved sulfolane solvent contained therein. A net kerosine raffinate stream leaves water-wash tower 15 via line 17 at a rate of 63.5 mols./hr. and a temperature of 100° F. This kerosine raffinate passes via line 17 into storage facilities, not shown, at a rate of 1010 barrels per stream day and has the required specification smoke point of 35 mm.

A rich aqueous stream leaves the bottom of water-wash tower 15 via line 18 at a rate of 82.0 mols./hr. This stream comprises 81.0 mols./hr. of water and 1.0 mols./hr. of primary sulfolane solvent. The stream is passed into a water still 19 wherein the secondary solvent comprising water is separated from the primary solvent comprising chemical sulfolane. The water still is operated at a reboiler temperature of about 350° F. to produce a sulfolane solvent having substantial freedom from water. This lean sulfolane solvent leaves the bottom of water still 19 via line 8 at a rate of 1.0 mols./hr. and a temperature of about 340° F., and it enters line 3 wherein it is combined with the lean sulfolane solvent leaving the bottom of fractionator 6 as disclosed hereinabove.

An overhead vapor leaves the top of water still 19 via line 20 at a temperature of 170° F. and a pressure of 310 mm. of mercury absolute. This overhead vapor comprises water vapor having substantial freedom from the sulfolane solvent, and it passes into a condenser 21 at a rate of 108.5 mols./hr. The water vapor is cooled and condensed therein to a temperature of 100° F., and it passes via line 22 into a receiver 23. The condensed water is separated into two portions at receiver 23. A first portion passes via line 24 at a rate of 27.5 mols./hr. into the top of water still 19 to provide the reflux required within the water still. A second portion of the water is withdrawn from receiver 23 via line 16 at a rate of 81.0 mols./hr., and the second portion is sent into the top of

water-wash tower 15 to provide the necessary lean aqueous solvent disclosed hereinabove.

PREFERRED EMBODIMENTS

The foregoing example provides an embodiment wherein the inventive process recovers a primary solvent from a kerosine raffinate, and wherein the primary solvent comprises chemical sulfolane. Those skilled in the art will realize, however, that the process illustrated hereinabove by the foregoing example, is not limited to that specific hydrocarbon fraction or that specific solvent composition. The inventive process will find application in any extraction system wherein the raffinate phase inherently produces a mist of free primary solvent phase upon cooling. In particular, it should be noted that the present invention has application in aromatic extraction processes utilizing glycol solvents since the misting problem is also prevalent in glycol solvent systems.

In addition, it should be noted that in the foregoing example the ratio of the hydrocarbon phase to the non-hydrocarbon phase in the conditioning zone was 2:1. That is to say, two moles of kerosine raffinate were contracted with one mole of lean solvent by combining the stream of line 9 with the stream in line 4. But as noted hereinabove the ratio of hydrocarbon phase to non-hydrocarbon phase may be in the range of from 5:1 to 1:1. This ratio will vary with each specific application of the inventive process since specific operating conditions will dictate the ratio required. It is obvious that the effectiveness of the present invention is influenced not only by the rate of circulation of the primary solvent stream of line 9 to give the desired ratio, but also by the degree of turbulence within the conditioning zone comprising line 4, heat exchanger 10, and line 11. Furthermore, the effectiveness of the inventive process is influenced by the temperature of the raffinate stream entering the conditioning zone, the solvent content of the raffinate stream entering the conditioning zone, and the degree of cooling occurring within the conditioning zone. It must be further noted that the solvent content of the non-aromatic raffinate will vary since it is dependent upon the temperature level of the preceding aromatic extraction process unit (extractor 2), the mole percent of aromatics remaining in the raffinate, and the amount of solvent physically entrained in the raffinate. It is, therefore, not possible to define specifically the rate of circulation of the lean solvent stream to the conditioning zone which will be required to effectuate the proper elimination of solvent mist. However, by utilizing the teachings hereinabove, those skilled in the art will be able to determine the ratio of hydrocarbon phase to non-hydrocarbon phase required for any solvent system, to produce a conditioned raffinate substantially free of primary solvent mist, and thereby render the raffinate more readily extractable in the subsequent aqueous extraction zone.

The method of operation of the inventive process will be readily apparent to those skilled in the art from the teachings which have been presented hereinabove. In addition, the advantages of the inventive process are equally clear.

In particular, the inventive process provides for maximum recovery of primary solvent from a solvent-containing raffinate with a minimum of capital cost and a minimum of utility expenditure. If the raffinate is directly sent into the secondary extraction zone (water-wash tower 15) without prior conditioning in the conditioning zone and subsequent phase separation in accordance with the practice of the inventive process, the water-wash tower must be designed to recover the full solvent content of the raffinate. That is to say, the secondary extraction zone must recover both the solvent of solution and the free solvent mist contained within the raffinate phase. In order to accomplish this, the secondary extraction zone must contain a substantially greater number of contact stages and it also must have a larger diameter due to the greater amount of water circulation required within water-wash

tower 15. Similarly, water still 19 must be larger and the capital and utility costs will therefore be substantially greater than those incurred by the inventive process.

As noted hereinabove, the inventive process requires that the raffinate and the primary solvent phase be contacted within the conditioning zone in a region of high turbulence. In the example which has been disclosed hereinabove in reference to the drawing, sufficient turbulence was provided by line 4, heat exchanger 10, and line 9. In particular, the passage of the solvent phase and raffinate phase across the cooling tubes within heat exchanger 10 provides a high degree of turbulence. However, it is within the scope of the present invention to provide various mixing devices within the conditioning zone. For example, a mixing device may be installed in line 4 immediately before heat exchanger 10. The mixing device may comprise an in-line mixer having a motor-driven propeller or it may comprise a turbine mixer. Additionally, such a mixing device may comprise a series of mixing orifices, or any other suitable mixing apparatus may be provided in line 4 in order to obtain the high degree of turbulence which is required for contacting the raffinate hydrocarbon phase with the non-hydrocarbon solvent phase. It is also within the scope of this invention to provide such a mixing apparatus in line 11 after the two phases have been cooled in heat exchanger 10. However, the preferred embodiment when installing a mixing device in the conditioning zone is to provide the device immediately ahead of the heat exchanger 10.

It is also within the scope of the present invention to eliminate the separator 12 and pass the mixture of lean solvent phase and conditioned raffinate phase from the conditioning zone directly into the bottom of the water-wash tower 15. In such an embodiment, the two phases will be separated in the bottom of the water-wash tower 15, which will thus provide a separation zone integrated within the aqueous extraction zone. The raffinate phase will thereafter pass upward through the contact stages in the normal manner, while the solvent phase will pass out the bottom of the tower with the aqueous phase. However, this is not a preferred embodiment since if the separation zone is provided in the bottom of the water-wash tower 15, there is added an additional utility load on the water still 19 since the entire solvent phase must then be passed into column 19.

Similar modifications in the equipment and process flow of the instant invention will be readily apparent to those skilled in the art, but such modifications should not be construed to detract from the broadness of the present invention.

However, it may now be summarized that in a preferred embodiment, the present invention comprises a process for recovery of an aromatic extract and recovery of a non-aromatic raffinate from a primary solvent extraction process which comprises: (a) passing a mixed hydrocarbon feed stock into a primary extraction zone, wherein said feed stock is contacted under extraction conditions with a hereinafter specified first stream of water soluble primary solvent; (b) passing a second primary solvent stream containing aromatic hydrocarbons from said primary extraction zone into a distillation zone maintained under conditions sufficient to produce an aromatic extract, and to produce a lean primary solvent having substantial freedom from aromatic hydrocarbons; (c) passing a first portion of said lean primary solvent into said primary extraction zone as said first primary solvent stream specified; (d) withdrawing from said primary extraction zone a first non-aromatic raffinate stream containing primary solvent at a first concentration; (e) mixing and cooling said first raffinate stream with a second portion of said lean primary solvent in a conditioning zone under conditions sufficient to produce a conditioned raffinate containing primary solvent at a second concentration below said first concentration and thereby render said raffinate stream more readily extractible in an aqueous extraction zone

specified; (f) passing the resulting mixture into a phase separation zone maintained under conditions sufficient to produce a third primary solvent stream and a second raffinate stream comprising said conditioned raffinate; (g) passing said second raffinate into said specified aqueous extraction zone, wherein said conditioned raffinate is contacted under extraction conditions with a first stream of aqueous secondary solvent; (h) withdrawing from said aqueous extraction zone a second stream of aqueous secondary solvent containing primary solvent; (i) passing said third primary solvent stream from said phase separation zone into said distillation zone; (j) recovering said aromatic extract from said distillation zone; and, (k) recovering from said aqueous extraction zone a third raffinate stream having substantial freedom from primary solvent.

The invention claimed:

1. Primary solvent extraction process for recovery of an aromatic extract and recovery of a non-aromatic raffinate, which comprises:

- (a) passing a mixed hydrocarbon feed stock into a primary extraction zone, wherein said feed stock is contacted under extraction conditions with a hereinafter specified first stream of water soluble primary solvent selective for aromatics;
- (b) passing a second primary solvent stream containing aromatic hydrocarbons from said primary extraction zone into a distillation zone maintained under conditions sufficient to produce an aromatic extract, and to produce a lean primary solvent having substantial freedom from aromatic hydrocarbons;
- (c) passing a first portion of said lean primary solvent into said primary extraction zone as said first primary solvent stream specified;
- (d) withdrawing from said primary extraction zone a first non-aromatic raffinate stream containing primary solvent at a first concentration;
- (e) mixing and cooling said first raffinate stream with a second portion of said lean primary solvent in a conditioning zone under conditions sufficient to produce a conditioned raffinate containing primary solvent at a second concentration below said first concentration and thereby render said raffinate stream more readily extractible in an aqueous extraction zone specified hereinafter;
- (f) passing the resulting total mixture into a phase separation zone maintained under conditions sufficient to produce a third primary solvent stream and a second raffinate stream comprising said conditioned raffinate;
- (g) passing said second raffinate stream into said specified aqueous extraction zone, wherein said conditioned raffinate is contacted under extraction conditions with a first stream of aqueous secondary solvent;
- (h) withdrawing from said aqueous extraction zone a second stream of aqueous secondary solvent containing primary solvent;
- (i) passing said third primary solvent stream from said phase separation zone into said distillation zone;
- (j) recovering said aromatic extract from said distillation zone; and
- (k) recovering from said aqueous extraction zone a third raffinate stream having substantial freedom from primary solvent.

2. Process of claim 1 wherein said second stream of aqueous secondary solvent is fractionally distilled to provide a primary solvent fraction and said primary solvent fraction is passed into said primary extraction zone.

3. Process of claim 1 wherein said second stream of aqueous secondary solvent is fractionally distilled to provide an aqueous secondary solvent fraction having substantial freedom from primary solvent, and said secondary solvent fraction is passed into said aqueous extraction

11

zone to provide at least a portion of said first stream of aqueous secondary solvent.

4. Process of claim 1 wherein said second portion of lean primary solvent is mixed with said first raffinate stream in a molar ratio in the range of from 1:1 to 1:5.

5. Process of claim 1 wherein said solvent comprises a sulfolane-type chemical of the general formula:

wherein R_1 , R_2 , R_3 and R_4 are independently selected from the group consisting of a hydrogen atom, an alkyl group having from one to ten carbon atoms, an arylalkyl radical having from one to twelve carbon atoms, and an alkoxy radical having from one to eight carbon atoms.

6. Process of claim 5 wherein said solvent comprises sulfolane.

12

7. Process of claim 1 wherein said solvent comprises a sulfolene selected from the group consisting of 2-sulfolene and 3-sulfolene.

8. Process of claim 1 wherein said solvent comprises at least one polyalkylene glycol.

9. Process of claim 8 wherein said solvent comprises at least one of the group consisting of diethylene glycol, dipropylene glycol, and triethylene glycol.
